COMPOUND CLARIFIER

William E. Geissler, Ossining, N. Y., assignor to
The Dorr Company, New York, N. Y., a corpora-
tion of Delaware

Application December 1, 1941, Serial No. 421,171

14 Claims. (Cl. 127—13)

The general object of the present invention is to provide improved apparatus for use in the continuous clarification of liquids by sedimentation and decantation, and particularly for use in the compound clarification of two liquids received from different sources and having different characteristics in a single multitray clarifier structure.

More specifically, the object of the invention is to provide a single multitray clarifying machine adapted for use in the compound clarification of the primary juice and secondary juice extracted from sugar cane in initial and subsequent portions, respectively, of a sugar cane milling train or circuit of the usual type, such secondary juice has a lower sugar content and is of lower purity and ordinarily is more difficult to clarify though smaller in volume than the simultaneously produced primary juice.

Now, and in recent years, the clarification method, commonly called "compound clarification" which is disclosed and claimed in the Petree Patent No. 1,625,680, granted April 19, 1927, has been in extensive, wide spread and successful use in clarifying sugar cane juice, and generally regarded as the most efficient and desirable method practically available for the purpose. That method comprises two separate continuous clarifying actions in each of which clarified liquid is separated from "mud," which includes the solids separated from the clarified liquid subjected to the clarifying action. Furthermore, the liquid subjected to one of the two clarifying actions is a mixture including the clarified liquid product of the other action and the relatively rich primary juice separated from the sugar cane in an initial portion of the milling circuit, and the liquid subjected to the other clarifying action includes the relatively weak juice extracted from the sugar cane in a secondary portion of the milling circuit, and also includes the mud produced in the clarification of the mixture including the primary juice.

In compound clarification as heretofore practiced, the two clarifying actions have been effected in separate clarifiers, each of which is customarily a multitray clarifier. By the use of a single clarifier constructed in accordance with the present invention, in lieu of the two separate clarifiers heretofore required for compound clarification, I simplify the clarifying operation, and reduce the construction, operation and maintenance costs of the apparatus required for the clarification of a given amount of cane sugar juice, and also reduce the floor and housing space required.

My improved multitray clarifier comprises a plurality of superposed clarifying compartments and two receiving chambers respectively above and connected to upper and lower groups of said compartments, to thereby form two separate clarifying units, each including one of said chambers and the clarifier compartment or compartments connected thereto, and also comprises mud rakes working in the different compartments of the two units and carried by and forming a part of a common rotating structure including a vertical column centrally disposed in the clarifier said rotating structure preferably includes agitating elements in the receiving chambers of the two units which serve to flocculate the liquid therein prior to its flow into the corresponding clarifying compartments.

My improved clarifier may include various arrangements of the two receiving chambers and associated clarifying compartments, and of the conduit or flow path provisions for the passage of liquid from each receiving chamber into the associated clarifying compartments.

In a preferred form of the present invention for use in clarifying sugar cane juice, the secondary juice receiving chamber is located in the upper portion of the clarifier, and is of a diameter less than the clarifier diameter, and the primary juice receiving chamber comprises a central portion beneath the secondary receiving chamber and an annular portion surrounding the secondary chamber. This preferred arrangement of the two receiving chambers contributes to and facilitates the provision of means of desirable form for the removal of scum from the two receiving chambers, and makes it practically feasible and desirable to provide separate flow channels in said central column for the passage of liquid from the two receiving chambers to the clarifying compartments respectively associated with those chambers.

Preferably, the clarified liquid is withdrawn from one or more clarifying compartments of each unit through uprising overflow connections of the type commonly employed in multitray clarifiers, and all having their discharge ends at about the same level. Each such connection may advantageously include provisions for independently raising and lowering the discharge end of the connection, such as are customarily employed in regulating the relative overflows of clarified juice from different clarifying compartments of an ordinary multitray clarifier. Such clarified juice overflow connections serve the special purpose in my improved clarifier, of insuring that in normal

operation, approximately the same hydrostatic pressures in the two clarifying units will exist at every liquid level common to the two units. The maintenance of such common hydrostatic pressures in the two units eliminates the possibility that in normal operation a partition separating adjacent compartments of the two units will be subjected to the harmful mechanical stresses to which it might be subjected if relative liquid levels in the two units varied substantially. The maintenance of such common pressures also minimizes the tendency to flow from one unit into the other through a joint space between the center column of the rotating structure and the margin of the central opening in a partition separating adjacent compartments included in different units.

Advantageously I provide a joint seal between the rotating structure and the partition separating the lower compartment of one unit from a subjacent compartment of the other unit, which is normally effective to prevent flow from one compartment into the other, but which operates like a safety valve to permit such flow on the development of an abnormal differential pressure, such as may occur in filling or emptying the clarifier at the beginning or end of a grinding season, or in the course of a clarifier cleaning or repair operation.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of the invention.

Of the drawings:

Fig. 1 is a flow sheet diagrammatically illustrating the use of a preferred form of my improved clarifier in association with a sugar cane mill of conventional type;

Fig. 2 is a plan view of the clarifier shown diagrammatically in Fig. 1;

Fig. 3 is an elevation of the clarifier shown in Fig. 2, but with some clarifier elements angularly displaced from their positions correctly shown in Fig. 2;

Fig. 4 is a vertical section illustrating one seal associated with the rotatable central column of the clarifier shown in Figs. 1-3, and Fig. 5 is a vertical section illustrating a second seal associated with said central column;

Fig. 6 is a partial section on the line 6-6 of Fig. 3;

Fig. 7 is a somewhat diagrammatic sectional elevation, and Fig. 8 is a plan, of a modified form of clarifier; and

Fig. 9 is a somewhat diagrammatic sectional elevation of a third form of a clarifier.

In Fig. 1 I have illustrated diagrammatically the use of a preferred form of the present invention in connection with a sugar cane mill which is of conventional type, and which is associated with my improved clarifier and with juice heating apparatus and a source of maceration water, by piping of the character commonly used in associating a sugar cane mill with apparatus for the compound clarification of sugar juice.

As shown in Fig. 1 the sugar cane mill circuit includes a pair of disintegrating rolls A, and four three roll grinding mills, A', A², A³ and A⁴ through which the sugar cane passes successively

after leaving the rolls A. The liquid expressed from the cane by the rolls A and primary mill A' passes into the primary juice collection box B'. The juice passes from the box B' through a pipe 1 to juice treating apparatus C in which the juice is heated and limed in the customary manner, and from which the juice passes through a pipe 2 to the primary juice receiving chamber D of a multitray clarifier E. The juice expressed from the cane by the secondary mill A², is collected in a juice box B² from which juice passes through a pipe 3 to a secondary juice heating and liming device CA from which the juice passes through a pipe 4 to the secondary juice receiving chamber d of the clarifier E. Juice expressed from the cane by the mill A³ is collected in a juice receiving box B³ and passes from the latter through a pipe 5 back to the mill circuit where it is discharged as maceration liquid on to the cane passing from the primary mill A' to the secondary mill A². Juice expressed from the cane by the mill A⁴ is collected in the juice receiving box B⁴, and is returned to the mill circuit for use as maceration liquid by a pipe 6, which discharges onto the cane passing from the secondary mill A² to the third mill A³. Maceration water is discharged by a pipe 7 onto the cane passing from the third mill A³ to the fourth mill A⁴.

As shown in Fig. 1, secondary juice clarified as hereinafter described, passes from the clarifier E through a pipe 8 into the juice box B', so that the pipe 1 carries a mixture of unclarified primary juice and clarified secondary juice away from the juice box B'. The primary mud removed from the primary clarifying unit of the clarifier E as hereinafter described, is passed through a pipe 9 into the secondary juice receiving box B², and the pipe 3 thus carries away from the secondary juice box B² a mixture of unclarified secondary juice received from the mill A² with the mud separated from the primary juice in the clarifier E.

As shown best in Fig. 3, the secondary juice chamber d is separated from the receiving space 45 D by a pan-shaped partition member f smaller in diameter than and axially disposed in the shell or tank of the clarifier E. The partition f has a dished bottom and an uprising rim or peripheral portion f', and is carried by truss-like supports f² which extend radially inward from the peripheral wall of the clarifier E into engagement with rim f', and thus do not interfere with the hereinafter mentioned mud rakes and scum removing means. A dished partition F generally parallel to and spaced downwardly from the bottom wall of the partition f, forms the bottom wall of the receiving chamber D. The partition F extends to and is welded or otherwise attached at its periphery to the cylindrical wall of the tank E. The primary juice receiving chamber D thus includes a portion directly beneath chamber d, and an annular portion surrounding the chamber d and extending between its vertical wall f' and the surrounding wall of the tank E.

65 A series of dished partitions F', F², F³ and F⁴ generally similar in form to the partition F and each attached at its periphery to the tank shell, divides the portion of the tank space beneath the chamber D into three superposed primary juice clarifying compartments G', G², G³ and two secondary juice clarifying compartments g' and g². The compartment G' is directly beneath the receiving chamber D, and the compartment g² is directly above the conical bottom wall of the tank. The partition F³ separates the bottom

compartment G^3 of the primary juice clarifying unit from the top compartment g' of the secondary juice clarifying unit.

Each of the partition numbers f , F , F' , F^2 , F^3 and F^4 is formed with a central opening for the passage of the vertically disposed central column or hollow shaft H of a rotating structure carrying mud rake arms h , H' , H^2 , H^3 , H^4 and H^5 working above the partition walls f , F , F' , F^2 , F^3 and F^4 respectively, and each adapted to move settled sludge or mud towards the center of the receiving chamber or clarifying compartment in which it works. The rotating structure also includes mud rake arms H^6 working mud accumulating in the bottom compartment g^2 toward the central mud outlet E' in the bottom wall of the clarifier.

The shaft H also supports and rotates flocculating panels or grids H^7 and H^8 in the receiving chambers d and D , respectively, and scum removing sweeps H^9 and H^{10} at the inner and outer sides of the upper edge of the uprising rim portion f' of the wall of the receiving chamber d . The sweeps H^9 and H^{10} are adapted to work scum into outer and inner portions of a common scum channel or trough I , which extends from the tank periphery inward across the annular outer portion of the chamber D and across an outer portion of the chamber d . Curved arms H^{11} carried by the shaft H in the chamber d , and just short enough to clear the inner end of the scum channel I , work scum from the central portion of the chamber d into the path of the sweeps H^9 . The rotating structure including the shaft H is rotated at a suitably low speed by mechanism H^{12} above the tank E , which may be of the type customarily employed to rotate the mud raking structure of the multitray clarifier of conventional type, and hence need not be further described herein.

In the preferred clarifier construction illustrated, juice is fed from the receiving chambers D and d to the corresponding subjacent clarifying compartments by separate feed channels within and extending longitudinally of the tubular shaft H . Thus, as shown in Figs. 3 and 6, vertically extending partitions J in the upper portion of the hollow shaft H separate two primary juice distribution channels K at opposite sides of the shaft, from a central secondary juice channel L . The wall of the shaft H is cut away to form inlet ports K' , one opening into the upper end of each channel K from the portion of the receiving chamber D between the walls f and F . Each channel K is also provided with an outlet port K^2 opening to the clarifying compartment G' , and with a second outlet port K^3 opening to the compartment G^3 . As shown, the ports K^2 are simple openings or windows in the cylindrical wall of the pipe H . Each port K^3 , however, is in register with a corresponding pipe section K^4 , rectangular in cross section which is welded to and extends radially away from the pipe H . The pipes K^4 extend through and support a cylindrical member M coaxial with the pipe H and uniting with the latter to form an annular channel through which mud passes from the compartment G' into the lower portion of the compartment G^3 , as hereinafter explained. The pipe H is formed with inlet port openings L' through which secondary juice passes into the channel L from the secondary juice receiving chamber d , and with outlet ports L^2 which open from the channel into the compartment g' .

In Fig. 5 I have illustrated sealing provisions which may be employed to prevent leakage flow between the receiving chambers D and d through the joint between shaft H and the margin of the central opening in the partition element f . The sealing provisions shown in Fig. 5 comprises a flexible washer or gasket member N of cup leather form, mounted in an annular support N' carried by the partition element f and having a flexible edge bearing against the periphery of a metallic bearing ring N^2 welded on the shaft H . The character of the sealing provision just described is relatively unimportant, since the pressure differential tending to produce leakage between the two receiving chambers will never be large and some small leakage between the chambers will do no real harm.

It is definitely advantageous, however, to prevent leakage under normal conditions, and to permit leakage under abnormal conditions through the joint between the shaft H and the partition F^3 , and for this purpose, I advantageously make use of sealing provisions of the type illustrated in Fig. 4. Those provisions comprise a cylindrical member O attached to and forming a hollow uprising projection from the partition F^3 , and which surrounds the shaft H from which it is separated by an annular space. As shown, the member O comprises an out-turned flange portion O^1 at its lower end, which has its peripheral edge welded to a cylindrical boot F^5 secured to and depending from the partition F^3 at the margin of the central opening therein. The upper end of the member O extends into an air pocket O^2 open at its lower end and closed at its upper end, between the shaft H and a cylindrical hood member O^3 . The latter is spaced outwardly away from the portion of the member O which it overlaps, and has an upper end portion of reduced diameter, which is welded to the shaft H .

Under normal operating conditions, liquid flow over the top of the member O in either direction between the chambers G^3 and g' is prevented by air supplied to the air pocket O^2 by a pipe O^4 at a suitably low pressure which is limited by bleed ports O^5 formed in the wall of the pipe H at a level below the top of the member O and above the bottom of the member O^3 . Air bleeding through the ports O^5 into the feed channel L passes upward through that channel and passes out of the clarifier E through the upper end of the pipe H .

The sealing provisions shown in Fig. 4 should be so proportioned, and readily may be, that under normal operating conditions the difference between the pressures in the compartments G^3 and g' separated by the partition F^3 will never become high enough for liquid flow over the upper edge of the cylindrical member O . However, in filling the clarifier with juice at the beginning of an operating period and in emptying the clarifier at the end of such a period, there is a possibility that liquid will be passed into or withdrawn from one of the two clarifying units much more rapidly than into or from the other. This might result, for example in making the pressure in the compartment g' much higher than the pressure in the compartment G^3 , and thereby subject the partition F^3 to destructive stresses, if no means were provided for limiting the maximum value of the differential of said pressures.

The sealing provisions shown in Fig. 4 are adapted to suitably limit the maximum of value

of said differential. As will be apparent, as soon as the pressure in one of the two compartments exceeds that in the other by an amount corresponding to a liquid head equal to the distance between the upper edge of the member O and the lower edge of the member O², liquid will begin to flow through the space O² from one compartment into the other, and if the flow capacity of the flow path including said space, is sufficient for the purpose, as it may well be, it will act like a safety valve to prevent further increase in the pressure differential between the two compartments.

The amount of mud settling out of the secondary juice in the receiving chamber d of Fig. 3 is relatively quite small and is worked by the mud rake arms h through the ports L' into the feed channel and passes through the hollow shaft H down into the compartment g². Mud separated from the primary juice in the chamber D is also relatively small in amount and may be worked by the mud rakes H either through the ports K' into the feed channels K² and thence into the compartments G' and G² through the ports K² and K³, or directly into the compartment G' through the joint space between the partition F and shaft H. As shown, the member H is surrounded by a bearing ring or collar P immediately above the ports K², which is engaged by guide means P' secured to the dished partition F and centering the shaft H. The guide provisions P' need not be of a character to interfere with the passage of mud through the joint between the partition F and the member H.

Mud worked toward the center of the compartment G' by the mud rakes H² passes downward into the compartment G² through the annular space between the shaft H and a depending boot portion of the partition member F' surrounding the central opening in the latter. As shown, the last mentioned boot extends downward into the annular space surrounded by the previously mentioned member M. The latter guides the descending mud into the lower portion of the compartment G², and in conjunction with the tubes K⁴ keeps the juice entering the compartment G² from the feed channels K away from the mud entering the compartment from the compartment G'. Mud passing down through the member M, and mud worked into the center of the compartment by the mud rakes H³, pass into the compartment G³ through the annular channel between the shaft H and the boot depending from the partition F² at the margin of the central opening in the latter.

The mud rakes H⁴ work the mud received from the compartment G² and mud settling in the compartment G³ into an annular mud trough Q collectively formed by the member O and boot F⁵ which is of appreciably greater diameter than the shaft H, and is connected to the flange portion O' of the member O at a distance appreciably below the partition F³. The mud thus received in the trough Q passes away from the clarifier through an overflow connection comprising a horizontal pipe section Q' extending from the trough Q outwardly through the shell of the clarifier E and an external uprising pipe section Q² through the upper end of which mud overflows into a mud box Q³ at a level but little below the liquid level in the chamber D. The overflow level in the mud box Q³ may be adjusted by the vertical adjustment of a sleeve Q⁴ in telescopic relation with the upper end of the pipe section Q².

Mud settling in the compartment g' and moved

into the center of that compartment by the mud rakes H⁶, passes downward into the compartment g² through the annular channel between the shaft H and the depending center boot portion of the partition F⁴. The mud thus entering the compartment g², along with the mud settling in that compartment, and the mud passing downward through the shaft H, is worked to the central outlet E' in the bottom wall of the clarifier E by the mud rakes H⁶, and passes away from the clarifier through a mud draw-off pipe R, which discharges into a mud tank R'. The latter forms part of secondary mud handling apparatus of known type, which as shown in Fig. 1, comprises a rotary filter R² to which mud is moved from the tank R' by a pump R³, and from which a pump R⁴ withdraws relatively clear filtrate and passes it into admixture with the secondary juice flowing through the pipe 3 from the juice box B² to the secondary juice treating apparatus CA.

In the arrangement shown in Fig. 3, the juice clarified in each of the compartments G³ and g² passes into the compartment along with the mud from the compartment immediately above, though each of the clarifying compartments shown in Fig. 3 might have a separate feed inlet as do each of the clarifying compartments of the clarifiers shown in Figs. 7 and 8.

Clarified juice is withdrawn from the primary juice clarifying compartments G', G² and G³, through overflow pipe connections S', S² and S³, respectively, each of which includes an uprising portion external to the clarifier E, discharging at its upper end into a primary juice overflow box S. The discharge levels of each of said connections may be vertically adjusted in a known manner by an adjustment of the sleeve S⁴ in telescopic association with, and, in effect, forming the upper end of the corresponding overflow connection. The clarified juice passed into the juice box S, is withdrawn from the latter through a pipe S⁵, for transmission to the evaporating pans (not shown). Similarly, clarified juice is separately withdrawn from the secondary juice clarifying compartments g' and g² through overflow connections T' and T² including uprising portions which discharge at their upper ends into a secondary juice overflow box T. The discharge level of each of the overflow connections T' and T² may be adjusted by vertical adjustments of a sleeve T⁴ forming the upper end of the overflow connection. The clarified secondary juice passed into overflow box T passes from the latter through the previously mentioned pipe S to the juice box B' which receives primary juice from the rolls A and primary mill A'. Each of the overflow connections S', S², S³, T' and T² may receive juice through the usual circularly extending perforated pipe located in the upper peripheral portion of the corresponding clarifying compartment.

The intended operation of the apparatus collectively illustrated by Figs. 1 to 6 will be readily apparent from the foregoing statements and explanations. As those skilled in the art will understand, with the apparatus illustrated in Figs. 1 to 6 the compound clarification method can be practiced in the same manner and to the same advantages, as it has heretofore been practiced with apparatus including separate primary juice and secondary juice multitray clarifier. The use of the single clarifier which I have devised in lieu of the two separate clarifiers heretofore required for compound clarification, gives a number of practically important advantages including:

In general, the inherent cost of construction will be lower for my clarifier than for the separate primary and secondary clarifiers of the same aggregate clarifying capacity, in respect to each of the following items; foundation cost, tank cost, insulation cost, mud rake structure cost, and mud rake operation machinery cost.

Furthermore, the use of my improved single clarifier structure requires less floor space than the separate primary and secondary clarifiers heretofore used, and this will ordinarily make the inherent cost of the associated piping less with my clarifier than with separate primary and secondary clarifiers of the same aggregate capacity.

In general, also, the use of a single clarifier constructed in accordance with the present invention, in lieu of the two clarifiers heretofore required for compound clarification, should reduce the operation and maintenance costs by reducing the heat loss from the clarifying apparatus, by reducing the power consumption of the mud raking machinery, and by reducing the expense for labor and material necessary to maintain the clarifying apparatus in operation.

While I regard the apparatus shown in Figs. 1 to 6 as embodying the best form of my invention now known to me for practical use under ordinary conditions, it will be apparent that the general principles of the present invention may be used and the major advantages thereof may be obtained, with clarifying apparatus quite different from that illustrated in Figs. 1 to 6, and in Figs. 7 and 8 I have illustrated one clarifier, and in Fig. 9 a second clarifier, which differ in a number of respects from one another and from the clarifier shown in Figs. 1 to 6.

The clarifier EA shown in Figs. 7 and 8 comprises many parts which are similar, or analogous to parts of the clarifier first described, and which are designated so far as appears necessary in Figs. 7 and 8, by reference symbols differing from those used in Figs. 1 to 6 to describe corresponding parts, only by the inclusion of a second reference letter, A or a. The clarifier EA shown in Figs. 7 and 8 differs from the clarifier E first described principally in the form and disposition of its receiving chambers DA and da; in the manner in which the secondary juice is passed from its receiving chamber da into the associated secondary juice clarifying compartments ga' and ga²; in its mud handling provisions, and in details of its scum removing provisions.

The secondary juice receiving chamber da of the clarifier EA is annular in form extending between the cylindrical wall of the clarifier EA and the uprising portion fa' of a partition member fa, which is of angle-bar cross section and has its bottom portion extending into engagement with, and welded, or otherwise secured, to the cylindrical shell of the clarifier EA. The chamber DA separated from the chamber da by the partition fa, comprises a central cylindrical portion at the inner side of the partition fa and an annular portion underlying the partition fa.

Secondary juice passes from the chamber da to the clarifying compartment ga' and ga² through piping LA and shown as comprising a vertical conduit external to the shell of the clarifier EA which receives juice from the chamber da through a connection LA', and is provided adjacent its lower end with lateral outlet pipe branches LA² and LA³ which extend into the shell of the clarifier EA and discharge into the upper central portions of the secondary juice

clarifying compartments ga' and ga², respectively. Juice passes from the primary juice receiving chamber DA to the clarifying compartments GA' and GA², through feed conduits KA in the shaft HA as in the construction first described. The feed conduits KA have their lower ends extended and provided with outlet ports KA⁴ for the passage of primary juice from the chamber DA directly into the lowermost primary clarifying compartment GA³.

Mud passes from the receiving chamber DA and from the clarifying compartments GA' and GA² of the clarifier EA through a mud channel U, which comprises all of the bore of the horizontal shaft HA not occupied by the feed conduits KA. Mud enters the mud channel U from the chamber DA through inlet ports U', and enters said channel from the compartments GA' and GA² through ports U² and U³ respectively, and passes out of the channel U into the compartment GA³ through ports U⁴.

The shaft HA comprises an upper hollow section and a lower rod-like section HA²⁰. The latter passes through a central opening in the bottom wall of a conical mud pocket QA having its wall formed by a depressed central portion of the partition FA³. Primary mud passes from the pocket QA through a pipe QA' to a mud pump V which is external to the clarifier EA and discharges the mud through an uprising pipe QA² into a hopper QA³ above and opening into the pipe 4A in which it mixes with the secondary juice passing into the receiving chamber da.

Mud passes from the clarifying compartment ga' into the compartment ga² through a central depending boot portion FA⁵ of the intervening partition member FA⁴ depending from the latter at the margin of its central opening.

In Figs. 7 and 8, the scum trough IA extends into the clarifier EA from the cylindrical shell thereof for a radial distance less than the radial extent of the chamber da. Scum is worked over the uprising portions fa' of the partition member fa from the primary receiving chamber DA, and along the upper portion of the secondary receiving chamber da at the inner side of the scum trough IA, into the path of movement of the scum sweeps HA⁶ by curved scum sweep arms HA¹⁰. The joint between the shaft rod portion HA²⁰ and the margin of the opening in the partition FA³ through which said portion passes, is sealed by sealing provisions NA which may be similar in form and type to those illustrated in Fig. 5.

Except in respect to differences mentioned above, the clarifier EA may be similar in construction and operation to the clarifier EA first described.

The clarifier EB shown in Fig. 9 comprises many features similar to corresponding features of the clarifier shown in Figs. 7 and 8. The clarifier EB differs primarily from the clarifiers previously described, in that its secondary juice receiving chamber db is located below the partition FB³ separating the lowermost primary juice clarifying compartment GB³ from the upper secondary juice clarifying compartment gb'. As shown, the chamber db is surrounded by a cylindrical wall coaxial with the tank or shell of the clarifier EB, but of much smaller diameter. The chamber db opens at its lower end directly into an underlying portion of the compartment gb'. The lower secondary clarifying compartment gb³ of Fig. 9 receives juice to be clarified as well as mud, from the compartment gb' through the boot FA⁵ de-

pending from the partition FA⁴ separating the two compartments.

Primary juice passing from the feed chamber DB, which occupies the entire horizontal cross section of the clarifier EB, tank or shell above the partition FB, is distributed to the subjacent clarifying compartments GB', GB² and GB³, and mud is passed from the chamber DB and from the compartment GB' and GB² into the compartment GB³ exactly as in the clarifier EA. In Fig. 9, however, the partition FB³ between the compartment GB³ and gb' is generally in the form of a flat cone having its convex side uppermost but has a depressed peripheral portion which forms a mud pocket QB having its outer wall formed by a corresponding portion of the shell of the clarifier EB. Primary mud passes from the mud pocket QB through a pipe QB' into a mud tank QB² from which the mud is moved by a pump VB and its discharge pipe QB³ into the feed pipe 4B through which secondary juice admixed with the primary mud, is passed into the secondary juice receiving chamber db.

The pressures in the portions of the primary and secondary juice clarifying units adjacent but at opposite sides of the partition FB³, are adapted to be substantially equalized in normal operation, by the clarified juice overflow provisions QA which may be identical in principle with those shown in Fig. 1, and in Figs. 7 and 8.

Scum rising to the top of the liquid in the chamber DB of Fig. 9 is moved into a scum pocket within and adjacent the shell of the clarifier EB by curved sweepers hb. A valved scum draw off pipe W opens into the uppermost portion of the receiving chamber db, through which scum may be periodically removed from said chamber.

The three clarifier forms shown in sectional elevation in Figs. 3, 7 and 9 are generically alike in that each discloses a multitray clarifier including two clarifying units adapted for use in carrying out compound clarification, and each comprising a receiving chamber and a plurality of associated clarifying compartments.

Each of the three forms permits of the attainment of all of the general advantages obtainable by use of a single clarifier structure in lieu of the two separate clarifiers heretofore required for compound clarification including in particular the advantage of a single mud moving and flocculation mechanism. In each form, also, the clarified liquid overflow drawoff provisions insure the maintenance in normal operation of suitably related hydrostatic pressure conditions in flocculation clarifiers. Each form includes provisions of a type adapted to effect such agitation of liquid fed into each receiving chamber as is required for its proper flocculation. In this connection, attention is directed to the fact that in the form shown in Fig. 3, the stationary supports f² for the receiving chamber D contribute to the agitation and flocculation of the liquid in the receiving chamber D to which movements relative to the supports f² are given the liquid by the scum sweeps H¹⁰ above the supports f² and the mud rake arms H' and flocculation arms H² which move through the zone beneath the brackets f².

The three forms of apparatus shown in Figs. 3, 7 and 9 differ specifically in respect to the manner in which juice to be clarified is fed into the clarifying compartments. Thus, in Fig. 7 juice to be clarified is fed to each of the clarifying compartments GA², GA³, ga' and ga² along a flow path separate from the flow paths through

which each of those compartments receive settled solids from the compartment above it. In the form shown in Fig. 3 the lowermost compartments G³ and g² of the two units each receives juice to be clarified from the compartment directly above it along with the solids settled in the last mentioned compartment through the central opening in the partitions between the two compartments. In respect to the difference just mentioned between the forms shown in Figs. 3 and 7, the form shown in Fig. 3 is preferable under certain operating conditions, but not under others.

Thus, for example, under conditions of operation in which the settling or mud moved into the lowermost compartment GA³ or F⁷ are of relatively low density, their volume may exceed the aggregate volume of properly thickened mud and properly clarified juice which can be withdrawn from the compartment GA³ through its mud outlet QA⁸ and clarifying juice outlet SA³. In such a case, there will be back flow from the compartment GA³ through the feed inlet port KA⁴, with the result of some disturbance or upset in the clarifying performance of the compartment GA². Such back flow from the compartment G³ and resultant disturbance in the operation of compartment G² will not occur in the operation of the clarifier shown in Fig. 3 under similar operating conditions. With different conditions tending to higher density and lower volume of the solids separating from the clarified liquid in the compartments G' and G² of Fig. 3, the clarifying capacity of the compartment G³ may be somewhat less than it would be if mud to be thickened and juice to be clarified entered the compartment G³ through separate inlets such as those provided for in the compartment GA³ of Fig. 7.

In respect to the features just discussed, the arrangement shown in Fig. 9 is like the arrangement shown in Fig. 7 insofar as the primary juice clarifying unit is concerned, and is like the form of Fig. 3 in respect to the operation of the secondary juice clarifying unit.

While in accordance with the provisions of the statutes, I have illustrated and described the best forms of embodiment of my invention now known to me, it will be apparent to those skilled in the art that changes may be made in the form of the apparatus disclosed without departing from the spirit of my invention, as set forth in the appended claims and that in some cases certain features of my invention may be used to advantage without a corresponding use of other features.

Having now described my invention, what I claim as new and desire to secure by Letters Patent is:

1. Apparatus for the compound clarification of liquids having different characteristics, comprising a multitray clarifier including a tank and a plurality of superposed clarifying compartments and two receiving chambers within the tank, said chambers being, respectively above and associated with upper and lower groups of said compartments, each of said groups comprising one or more of said compartments, and means connecting each group and the associated chamber into a separate sedimentation and decantation unit including a flow path for the down flow of liquid from the chamber into the compartment or compartments of the unit, means for separately withdrawing clarified liquid from the two units, means for separately

withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, and a common mud compacting and moving means for the two units comprising a rotatable vertical column centrally disposed in the tank and mud rake arms carried by said column and extending into the different clarifying compartments.

2. A multi-tray clarifier for effecting compound clarification of two liquids having different characteristics, comprising in combination a tank and partitions therein subdividing the tank interior into two receiving chambers and a plurality of superposed clarifying compartments forming two separate sedimentation and decantation units each of which comprises one of said receiving chambers and one or more clarifying compartments, conduit connections to said chambers and compartments for passing one of said liquids into the receiving chamber of one of said units and for withdrawing clarified liquid from the second of said units and passing it into the last mentioned receiving chamber and for passing into the receiving chamber of the second of said units the second of said liquids and also for passing solids settled out of the liquid-treated in the first mentioned unit into the last mentioned receiving chamber, and conduit connections for withdrawing clarified liquid from the first mentioned unit and discharging it from the clarifier and for withdrawing from the second of said units solids settled out of the liquid treated therein and for passing those solids from the clarifier.

3. A multi-tray clarifier as specified in claim 2, comprising common mechanism for moving solids accumulating in the lower portion of each unit to the said conduit connection through which solids are passed from the unit.

4. Apparatus for the compound clarification of liquids having different characteristics, comprising a multitray clarifier including a tank and a plurality of superposed clarifying compartments and two receiving chambers within said tank, said receiving chambers being both above said compartments and respectively associated with upper and lower groups of said compartments, each of said groups comprising one or more of said compartments, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, and a common mud compacting and moving means for the two units comprising a rotatable vertical column centrally disposed in the tank and mud rake arms carried by said column and extending into the different clarifying compartments.

5. Apparatus for the compound clarification of liquids having different characteristics, com-

prising a multitray clarifier including a tank and a plurality of superposed clarifying compartments and two receiving chambers within said tank, said receiving chambers being respectively above and associated with upper and lower groups of said compartments, each of said groups comprising one or more of said compartments, and means connecting each group and the associated chamber into a separate sedimentation and decantation unit including a flow path for the downflow of liquid from the chamber into the compartment or compartments of the unit, means for separately withdrawing clarified liquid from the two units, uprising overflow pipe connections having their discharge ends at approximately the same level whereby said connections insure that in normal operation approximately the same hydro-static pressures will exist in the two clarified units at every liquid level common to the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, and a common mud compacting and moving means for the two units comprising a rotatable vertical column centrally disposed in the tank and mud rake arms carried by said column and extending into the different clarifying compartments.

6. Apparatus for the compound clarification of liquids having different characteristics, comprising a multitray clarifier including a tank and a plurality of superposed clarifying compartments and two receiving chambers within said tank, said chambers being both above said compartments and respectively associated with upper and lower groups of said compartments, one of said chambers extending circularly about each of said groups comprising one or more of said compartments, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, a common mud compacting and moving means for the two units comprising a rotatable vertical column centrally disposed in the tank and mud rake arms carried by said column and extending into the different clarifying compartments, and scum removing means including a common scum channel extending above each of said chambers and scum sweeping devices carried and moved by said column and extending into said chambers and moving scum collecting therein into said channel.

7. Apparatus for the compound clarification of liquids having different characteristics, comprising a multitray clarifier including a tank and a plurality of superposed clarifying compartments and two receiving chambers within said tank, said chambers being respectively above and associated with upper and lower groups of said compartments, each of said groups comprising one

or more of said compartments, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, a common mud compacting and moving means for the two units comprising a rotatable vertical column centrally disposed in the tank and mud rake arms carried by said column and extending into the different clarifying compartments, and flocculation arms carried by said column and extending into said receiving chambers.

8. Apparatus for the compound clarification of liquids having different characteristics, comprising a multitray clarifier tank structure enclosing a plurality of superposed clarifying compartments and two receiving chambers, respectively above and associated with upper and lower groups of said compartments, each of said groups comprising one or more of said compartments, said structure including superposed partitions forming the bottom walls of said chambers and compartments except the lowermost compartment, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, a common mud compacting and moving means for the two units comprising a rotatable vertical column centrally disposed in the tank and mud rake arms carried by said column and extending into the different clarifying compartments, each of said compartments being formed with a central opening through which said rotatable center column extends and means forming a seal between said column and each of said partitions which directly separates superposed portions of the two units, each such seal being operative to substantially prevent flow in normal operation between the two units through the opening in the corresponding partition.

9. Apparatus for the compound clarification of liquids having different characteristics, comprising a multitray clarifier including a tank and a plurality of superposed clarifying compartments and two receiving chambers within said tank, said receiving chambers being respectively above and associated with upper and lower groups of said compartments, one of said receiving chambers being coaxial with the tank and of a diameter less than the tank diameter, and the other of said chambers comprising a lower portion of the full diameter of the tank and extending under the first mentioned chamber and also comprising an uprising portion extending circularly about

the first mentioned chamber, each of said groups comprising one or more of said compartments, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, and a common mud compacting and moving means for the two units comprising a rotatable vertical column centrally disposed in the tank and mud rake arms carried by said column and extending into the different clarifying compartments, said vertical column being formed with channels which are included in the connecting means through which liquid flows from the two chambers into the clarifying compartments of the respective units.

10. Apparatus for the compound clarification of liquids having different characteristics, comprising a multitray clarifier tank structure enclosing a plurality of superposed clarifying compartments, two receiving chambers, respectively above and associated with upper and lower groups of said compartments, each of said groups comprising one or more of said compartments, said structure including superposed partitions forming the bottom walls of said chambers and of each of said compartments except the lowermost compartment, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, a common mud compacting and moving means for the two units comprising a rotatable vertical column centrally disposed in the tank and mud rake arms carried by said column and extending into the different clarifying compartments, and means forming a seal between said column and the partition forming the bottom wall of the lowermost compartment of said upper group of compartments operative to substantially prevent flow between the last mentioned compartment and the subjacent tank structure space through the central opening in the last mentioned partition when the difference between the pressure in the last mentioned compartment and the pressure in said space is that prevailing in normal operation, and to permit such flow when said difference in pressures exceeds that prevailing in normal operation.

11. Apparatus as specified in claim 10, in which the said seal forming means comprises spaced apart telescoping annular parts, one of which is carried by said column and unites with the latter to form an inverted trough extending circularly about said column, and the other of which

comprises a cylindrical flange extending outwardly into said trough, and means for passing air under pressure into said trough.

12. A multitray clarifier for compound clarification of liquids having different characteristics, comprising a tank and internal partitions dividing the tank space into a plurality of sections and comprising a plurality of horizontally extending partition members located at different levels and each separating two of said sections in superposed relation with one another, said sections being combined to form two separate sedimentation and decantation units, each of which comprises a clarifying portion comprising one or more of said sections and a receiving chamber, formed by another of said sections, which is above said clarifying portion and is connected to the latter to provide a flow path for the downflow of liquid into the clarifying portion from said receiving chamber, one of said receiving chambers having a peripheral wall extending about the tank axis and spaced inwardly from the peripheral wall of the tank and supported by connections between said walls, and the other of said chambers comprising a lower portion of the full diameter of the tank and extending under the first mentioned chamber and comprising an uprising portion extending circularly above the first mentioned portion between upper and lower levels respectively above the upper edge and below the lower edge of said connections, and conduit connections to said sections comprising means for separately withdrawing clarified liquid from each of the sections included in said clarifying portions, means for separately withdrawing mud from the lower portion of each unit, means for passing mud withdrawn from one unit and one of the first mentioned liquids into the receiving chamber of the other unit, and means for passing the clarified liquid withdrawn from the last mentioned unit and the second of the first mentioned liquids into the receiving chamber of said one unit, said means cooperating to normally maintain said tank space filled with liquid below a liquid level adjacent the upper end of the tank with the hydrostatic pressure of the liquid at any lower level substantially proportional to the distance between the two levels whereby the liquid pressures acting against the upper and lower sides of each of said partition members substantially balance one another.

13. Apparatus for the compound clarification of liquids having different characteristics, comprising a multitray clarifier including a plurality of superposed clarifying compartments, two receiving chambers, respectively above and associated with upper and lower groups of said compartments, one of said receiving chambers having a peripheral wall extending about the tank axis and spaced inwardly from the peripheral wall of the tank and supported by connections between said walls and the other of said chambers comprising a lower portion of the full diameter of the tank and extending under the first mentioned chamber and comprising an uprising portion extending circularly above the first mentioned portion between upper and lower levels respectively above the upper edge and below the lower edge of said connection, each of said groups comprising

one or more of said compartments, and means connecting each group and the associated chamber into a separate sedimentation and decantation unit including a flow path for the downflow of liquid from the chamber into the compartment or compartments of the unit, means for separately withdrawing clarified liquid from the two units, means for separately withdrawing mud from the two units, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, and a common mud compacting and moving means for the two units comprising a rotatable vertical column centrally disposed in the tank, mud rake arms carried by said column and extending into the different clarifying compartments, and scum removing means carried by said column and respectively extending over and under said connections.

14. A multitray clarifier for compound clarification of liquids having different characteristics, comprising a tank and internal partitions dividing the tank space into a plurality of sections and comprising a plurality of horizontally extending partition members located at different levels and each separating two of said sections in superposed relation with one another, said sections being combined to form two separate sedimentation and decantation units, each of which comprises a clarifying portion comprising one or more of said sections and a receiving chamber formed by another of said sections which is above said clarifying portion and is connected to the latter to provide a flow path for the downflow of liquid into the clarifying portion from said receiving chamber, and conduit connections to said sections comprising means for separately withdrawing clarified liquid from each of the sections included in said clarifying portions, means for separately withdrawing mud from the lower portion of each unit, means for passing mud withdrawn from one unit and one of the first mentioned liquids into the receiving chamber of the other unit, means for passing the clarified liquid withdrawn from the last mentioned unit and the second of the first mentioned liquids into the receiving chamber of said one unit, said means cooperating to normally maintain said tank space filled with liquid below a liquid level adjacent the upper end of the tank with the hydrostatic pressure of the liquid at any lower level substantially proportional to the distance between the two levels whereby the liquid pressures acting against the upper and lower sides of each of said partition members substantially balance one another, and a rotating structure comprising a vertical central column extending through said partition members and comprising mud rakes respectively above the different partition members and a vertical center column extending through said partition members and formed with vertically extending channels separately connecting the receiving chambers of the two units to the clarifying portions thereof and thereby providing the said flow path of each unit.

WILLIAM E. GEISSLER.
